Paul Gray

UNITED STATES PATENT OFFICE.

CHARLES HAMMER, OF HOLLIS COURT BOULEVARD, QUEENS COUNTY, NEW YORK.

METAL CAP OR CLOSURE.

Application filed February 2, 1925. Serial No. 6,196.

To all whom it may concern:

Be it known that I, CHARLES HAMMER, a citizen of the United States, residing at Hollis Court Boulevard, in the county Queens 5 and State of New York, have invented certain new and useful Improvements in Metal Caps or Closures, of which the following is a specification.

This invention relates to metal caps or 10 closures for glass containers or receptacles and to the method of making the same, and particularly to that style of cap commonly designated in the trade as "lug caps" for use on glass bottles or containers having multiple or divided threads whereby on rotating 15 or turning the cap it will be securely locked on the container, the object of the invention being to provide an improved reusable metal cap or closure of this class having a plurality of lug formed projections of increased 20 holding efficiency located at the lower edge of the cap flange or skirt.

One of the objects therefore of the present 25 invention is the provision of a metal cap or closure having an improved form of locking or holding lug which will engage or grip the threads of a glass container a considerable distance lengthwise of such lugs and grip the container threads with gradually 30 increasing efficiency on the turning of the cap on to the container thereby to tightly seal the container.

A further object of the invention is the 35 provision of a metal cap or closure having at its lower edge a combined bead or curled edge and a lug of the improved form herein described formed from such bead or curled edge, the construction of the lug being such that it will draw the cap more firmly down 40 upon the container and also give an increased or lengthened bearing surface upon the projection or thread of the container, so that the liability of the cap lug scratching and thereby tending to cause the glass container thread to break is avoided.

It has been found in practice that metal 45 caps having short lugs of practically flat formation on the thread engaging side of the lug have only a limited engagement with the container thread and consequently there are times, especially when the glass threads are not uniform or properly made, or of just the right size or formation, when the cap is not drawn down as firmly upon the

container as is desired, so that the cap in 55 the frequent handling or shipment of the container, tends to work off.

It has also been found from practical experience, especially when the glass threads are brittle as is sometimes the case, that 60 these short lugs having but a limited bearing surface upon the threads of the container, when quickly turned on, cause the glass threads of the container to break due to the fact, as has been found by experience, 65 that as the cap is turned on, the lugs coming into engagement suddenly at a small part only of the brittle glass thread, scratch and weaken it in the same manner as a glass cutter weakens a piece of glass by scratching, so that in the handling of the container thereafter and in the reuse of the 70 cap, portions of the glass thread break off.

It is therefore the object of the present invention to provide an improved locking or 75 holding lug that will not only draw the cap more firmly down upon the container but will gradually engage the glass thread and have an increased or lengthened bearing surface upon such thread, so that the cap lug 80 will thus engage the container thread gradually throughout a considerable length of the thread and be brought into engagement with that glass thread by gradually increasing efficiency rather than by sudden force, 85 and thus obviate any mutilation of the thread.

Therefore the present improvement is an important one when it is remembered that millions of glass containers are capped and 90 handled per day and that frequently some have the threads much more brittle than others.

In my prior Patent 1,079,238 dated November 18, 1913 the bead was provided with 95 relatively short locking lugs or projections having substantially flat glass thread engaging faces and that cap has been a very successful cap, many millions thereof having been made, and in daily use, and the object of the present invention is to improve that cap by providing a lug that will more firmly draw the cap on to the container and give an increased bearing surface on the container thread, and which will also take up the necessary variations in the glass threads of the container, and in which the curled edge, the holding lugs or locking projections and the 100 105

corrugations will all cooperate to stiffen the cap and insure greater rigidity to the lugs than was even possible in the cap of the patent referred to.

5 In the drawings accompanying and forming a part of this specification and in which one embodiment of the invention is shown, Fig. 1 is an enlarged perspective view illustrating a small size two lug metal cap of 10 this improved construction, the drawing having been made from a cap about one-third smaller than the size of cap shown; Fig. 2 is a detail, inside, enlarged view of a portion of the cap illustrating one of the improved 15 lugs; Fig. 3 is a cross sectional view of the cap in position to be turned on to a container; Fig. 4 is a cross sectional view of the cap and container taken on line 4—4 Fig. 3 looking in the direction of the arrows; Fig. 20 5 is a cross sectional view of the cap and container illustrating the relative position of the cap lugs and container threads when the cap is turned on to the container; Figs. 6, 7 and 8 are sectional views taken respectively on lines 6—6, 7—7 and 8—8 of Fig. 3, and illustrate the somewhat hollow or tubular formation of the lug, this tubular formation gradually increasing from the entering end of the lug to the rear thereof, especially 25 in the larger sizes of caps; and Fig. 9 illustrates in a general way the position of the cap lug and container thread when the cap is 30 on the container.

Similar characters of reference indicate 35 corresponding parts in the several views.

Before explaining in detail the present improvement and mode of operation thereof, I desire to have it understood that the invention is not limited to the details of construction and arrangement of parts which 40 are illustrated in the accompanying drawings, since the invention is capable of other embodiments, and that the phraseology which I employ is for the purpose of description and not of limitation.

I believe that I am the first to provide a metal cap or closure having a combined curled or beaded edge and a lengthened lug formed therefrom having an inclined thread engaging face, and which lug is formed from the bead or curled edge in a somewhat similar manner to that shown in my said prior patent, as by partially flattening or collapsing the beaded edge, so that it will gradually engage 50 the glass container thread and firmly draw the cap on to the container and at the same time have an increased bearing engagement of the cap lug on the glass thread throughout practically the entire length of 55 the lug, although such lug may be formed in other ways than that shown in my said patent, in other words, the first to provide a cap lug of the improved construction shown which will gradually engage the container thread and have a materially in-

creased bearing surface thereon and so avoid any danger of mutilating a brittle glass thread.

In the preferred form thereof shown the cap when of small size is provided with a pair of diametrically opposite lugs but the cap may have any desired number of lugs according to the size thereof, larger sizes of caps frequently having four such lugs.

In the metal cap shown it comprises a top 2 having the usual depressed groove 3 for contact with a suitable liner 4 for sealing the top of the container. This top is provided with a depending flange or skirt 5 shown of corrugated form, the corrugations 6 not only constituting a means for gripping the cap in the handling thereof but a reinforcing means to stiffen the flange and the lugs, but also providing an efficient means for the proper formation of the cap on the forming rolls. The lower edge of the skirt is strengthened as by bending, rolling or curling it preferably outwardly to form a reinforcing bead or curled edge 7, and this bead is not only useful in giving a pleasing appearance to the cap, preventing the cutting of the hands of the user and providing a sanitary cap in that the raw edge is concealed and protected against corrosion and the action of the elements, but is particularly useful in strengthening the flange and the lug itself, and also provides a means for forming the lugs therefrom at the lower edge of the flange of the improved form shown whereby they have increased strength and bearing efficiency.

At several places shown in the drawings as two, this reinforcing bead or curled edge is shown pressed upwardly toward the top of the cap and inwardly toward the center of the cap to form a pair of inwardly extending radial lugs 8, the outer face 9 of which is substantially at the same distance throughout the length of the lug from the top of the cap, but the inner or thread engaging face 10 of which is gradually inclined or tapered in the direction of the length of the lug, so that the lug is thus of wedge-shaped form, the thread engaging face 10 being of less distance from the top of the cap at the rear end of the lug than it is at the front or entering end. In other words, the inner wall or thread engaging face of the lug gradually lessens the distance between such face and the top of the cap, so that the lug is materially thicker at its rear end than at its front end due to the gradually increasing tubular or hollow formation of the lug. By forming the lug in this way it will be observed that it has considerable length and also sufficient width to properly and efficiently gradually grip the underside of the container thread 11 formed on a suitable glass container 12.

In this improved cap lug when formed

- in the manner just described, it will be observed that it has its outer face 9, that is its lower face when the cap is on the container, somewhat within the lower margin of the 5 bottom or outer face of the bead and therefore not flush with such bottom or outer face of the curled edge due to the fact that the metal of the curled edge is pressed upwardly and inwardly to form the lug.
- 10 By forming the lug of increased length, as herein described as well as of slightly tubular form, at least at certain parts thereof, the lug is not only materially strengthened by this formation, but is also materially 15 strengthened by the increased number of corrugations terminating above the lug and which may run from adjacent the top of the lug toward the top of the cap, so that by the combined strengthened lug formed bead 20 and the corrugations, when such are used, the cap can be made of relatively thin sheet metal or of any suitable material and yet have sufficient strength and resisting qualities to resist any ordinary strain that may 25 be placed upon the cap in the handling thereof.
- Furthermore it will be observed that this improved lug engages the glass thread practically throughout the entire length of the 30 long inclined face of the lug, and not just at a small part of the lug. The lug in practice will preferably have a taper or inclination that will substantially coincide with the inclination at the underside of the glass 35 thread, which is not possible with a relatively flat lug, and due to the way in which the lug is formed, it has a certain resilient or spring action when turned on to the thread of the container that will enable it not only 40 to compensate for any inequalities or variations at the underside of the thread but will enable it to be easily applied with, as it were, a cushioning effect, so as not to scratch or break the glass thread, especially when 45 this is of brittle construction.
- By actual tests, the cap turns on very easily and with a gradual gripping effect and without any sudden or harsh action upon the glass thread, and although it can be turned 50 off easily it grips the thread thoroughly so that the cap will not jar off in the ordinary handling of the container, while the cap is effectively drawn down to insure a tight seal between the liner and the mouth or upper 55 edge of the container.
- In some forms of glass containers the threads may have a stop face 13 (see Fig. 9)
- formed by or adjacent to the seam of the glass which serves to limit the turning on of the cap and prevent the distortion of the 60 cap and its lug.
- The efficiency of the cap has been so thoroughly demonstrated that the demand for it is not only very large but is daily increasing 65
- It is to be understood that by describing 70 in detail herein any particular form, structure or arrangement, it is not intended to limit the invention beyond the terms of the several claims or the requirements of the prior art.
- Having thus explained the nature of my 75 said invention and described a way of constructing and using the same, although without attempting to set forth all of the forms in which it may be made, or all of the modes 80 of its use, I claim:
1. A metal closure for glass containers, comprising a top having a depending skirt provided with a beaded or curled lower edge flattened or pressed upwardly and inwardly 85 to form a relatively long inwardly extending locking lug having its inner face inclined to the top of the cap.
  2. A metal closure for glass containers, 90 comprising a top having a depending skirt provided with a beaded or curled lower edge flattened or pressed upwardly and inwardly to form a relatively long inwardly extending locking lug having its inner face inclined to the top of the cap and its outer face inside 95 the outer margin of such curled edge.
  3. A metal closure for glass containers comprising a top having a depending reinforced or corrugated skirt provided with a curled or beaded lower edge, said curled edge 100 being flattened at intervals to provide in- struck relatively long locking lugs, the inner face of which is inclined and the outer face of which is within the outer margin of the curled edge.
  4. The method of making metal caps for glass containers, which consists in forming a cap having a top provided with a depending skirt or flange, curling the lower edge 105 thereof, and compressing such curled edge inwardly toward the top and toward the center of the cap to form a relatively long lug having an inclined glass thread-engaging face and an outer face inside the outer margin of the curled edge.

Signed at Brooklyn, New York, this 29th day of January 1925.

CHARLES HAMMER.
